United States Patent Office.

RICHARD SMITH, OF SHERBROOK, CANADA.

Letters Patent No. 91,780, dated June 22, 1869.

IMPROVED MACHINE FOR FINISHING PAPER BOXES.

The Schedule referred to in these Letters Patent and making part of the same.

To all whom it may concern:

Be it known that I, RICHARD SMITH, of Sherbrook, in the Province of Quebec, in the Dominion of Canada, have invented a new and useful Finishing-Press for Paper Boxes; and I do hereby declare the following to be a full and correct description of the same, reference being had to the accompanying drawings, in which—

Figure 1 is a perspective view of the machine, seen from the front.

Figure 2 is a side view of the same.

Figures 3, 4, and 5, are details.

Figure 6 is a vertical central diagonal section of the machine on line $z-z$ of fig. 7.

Figure 7 is a top view of the table, with the gallows removed.

The same part is marked by the same letter of reference wherever it occurs.

The object of this invention is to apply to paper boxes made direct from the pulp, and when partially dry, a second or finishing-pressure, in order to condense the material, and impart to the boxes a smooth surface and sharp, well-defined outlines.

The invention consists of a machine of the peculiar construction hereinafter described, for effecting the object above specified. It is intended to be used in conjunction with the machine for making paper boxes direct from the pulp, for which I received a patent, November 17, 1868, or with any other machine for the same purpose.

To enable others to make and use my machine, I will proceed to describe its construction and operation, referring to the accompanying sheets of drawings by the letters of reference marked thereon.

The machine stands upon a square case or bed-plate, z , from which rise four stout columns, y y y y , supporting the table z , which is of the same size and form as the bed-plate z .

A hollow cylinder, w , is attached to the lower side of the table z by bolts b , passing through flanges a , and projects downward toward the base Z .

Its upper end is received in an opening in the table X , as shown in fig. 6, and on it rests the form E , on which the boxes to be pressed are placed.

From the upper side of table H rises the gallows V , supporting the mechanism for operating a cylindrical plunger, R , which works in a bracket, S , having a cylindrical bore of the proper calibre to receive said plunger, and allow it to reciprocate vertically in it.

This plunger is operated by means of the handle H , attached to the end of the rock-shaft I , which turns in brackets U , projecting from the rear of the gallows V . (See fig. 2.)

This rock-shaft has a forked arm, M , to which one end of the link N is pivoted, the other end of said link being pivoted to the arms $O P$, which form a toggle-joint for operating the plunger R . The upper end of arm O is pivoted to a forked lag, Q , projecting from

the front of the gallows V . The lower end of arm P is hinged to plunger R . When the handle H is drawn forward, the plunger R is driven down, and when the handle H is thrown back, the plunger rises. The function of plunger R is to drive down the spring-plunger w .

To the bed-plate Z is attached a forked stud, z , which serves as a fulcrum for treadle-lever J , which is pivoted to it.

To the inner end of this lever is pivoted the lower end of the rod u , the upper end of which is attached to an annular clearer, v , which surrounds the former E , and rises and falls in obedience to the movements of treadle J ; rising when the treadle is depressed, and falling when it is released. The function of this clearer is to throw out the finished box from the machine.

On the table X , and surrounding the form E , are four jaws, $A B C D$, working in guides $G G G G$, and operated by four toggles. The arrangement of these jaws and toggles is clearly shown in fig. 7. Jaw A is operated by toggle-arms $i j$, pivoted to the fixed stud h ; jaw B , by arms $s t$, pivoted to stud r ; jaw C , by arms $m n$, pivoted to stud l ; and jaw D by arms $p q$, pivoted to stud o .

The toggles which operate the jaws are operated by levers F and K , (having their fulcrum at f and k), which are respectively connected to them by the links $e d$ and $e g$. (See figs. 1, 2, and 6.)

Each of the levers F and K operates two pairs of toggle-arms.

Above the guides G , and diagonally in reference to the lines of the jaws, a slide, L , reciprocates horizontally in ways L' , attached to the gallows V .

Fig. 3 is a detached perspective view of this slide, and fig. 5 is a transverse vertical section of it, through the spring-plunger w .

In the forward end of this slide is a vertical cylindrical perforation, which receives the cylindrical plunger w , allowing it free vertical motion.

Similar but smaller holes are connected with the larger one, and receive spiral springs (see fig. 5) which react upwards.

A circular plate, x , is screwed to the lower end of plunger w , and another plate, y , (fig. 4,) is screwed on to its upper end.

Against the ends of this plate y , the spiral springs act to raise the plunger w till the upper surface of plate y is flush with the upper surface of slide L .

Pressure applied to plate y forces the plunger w down. When the pressure is removed, the spiral springs force it up to its original position. This pressure is applied by plunger R , operated by handle H .

The slide L has a handle on its forward end, and is operated by hand, being drawn forward by the workman when the upper pressure is to be applied, and shoved back when the pressure is relieved.

The sliding movement is given to L, to allow the form E to be uncovered for the insertion and delivery of the box, while the plunger w can be brought over it at the proper time for giving the desired pressure to the bottom of the box.

The operation of the machine is as follows:

The slide L being thrown back, and the jaws A B C D open, the paper box or hollow article, which has been made of pulp and partially dried, is placed on the form E, which is made of the exact size and shape to receive it. The lever F is then brought up till the jaws A B come in contact with the edges of the jaws C D. Lever K is then raised till the jaws C D are driven in against the sides of the box. The slide L is now drawn forward, till the plunger w is directly over the form E, when the handle H is drawn forward, which drives down the plate x x upon the bottom of the box. The pressure is now complete. The handle H is thrown back, and the plunger w rises. Levers K and F are depressed, to release the jaws A B C D, and the foot is applied to the treadle J, which raises the clearer v, and throws out the finished box.

It is obvious that the form, and size of the form, jaws, and plunger, can be varied to any extent to suit the size and shape of the article to be pressed.

The form E may be made hollow, or in halves, and so that a blast of air may be applied to throw off the box when pressed.

The ends of the jaws that come in contact with the

box may be perforated and covered with wire gauze, to allow of the escape of water, or they may be engraved with any desired pattern, so as to emboss the surface of the box, if preferred.

Having thus fully described my invention,

What I claim, and desire to secure by Letters Patent, is—

1. A machine for imparting a finishing-pressure to boxes and hollow articles made from paper-pulp, by receiving them on a form, and subjecting them to lateral and vertical compression, applied by means of jaws and a plunger, substantially in the manner described.

2. The jaws A B C D, with their respective toggles and levers arranged and operating as specified.

3. The slide L, with its spring plunger w, constructed, arranged, and operating as described.

4. The form E, arranged for conjoint operation with the jaws A B C D and the plunger w, in the manner set forth.

5. The clearer v, constructed, arranged, and operating in the manner and for the purpose set forth.

The above specification of my said invention, signed and witnessed at Lawrence, this 14th day of May, A. D. 1869.

RICHARD SMITH.
